(57) **CLAIM**

We claim the ornamental design for an iron blade grille, as shown and described.

DESCRIPTION

FIG. 1 is a front view of the iron blade grille according to our invention.

FIG. 2 is a rear view of the iron blade grille.

FIG. 3 is a top view of the iron blade grille

FIG. 4 is a bottom view of the iron blade grille.

FIG. 5 is a right side view of the iron blade grille; and, FIG. 6 is a left side view of the iron blade grille.

The broken lines are shown for illustrative purposes only and from no part of the claimed design.
